FLAG MOUNTING

Linus Schillinger, Syracuse, N. Y.

Application December 21, 1942, Serial No. 469,632

2 Claims. (Cl. 116—174)

This invention relates to methods and means for mounting flags and pennants.

The principal object of the invention is to provide a device which will keep a flag or pennant unfurled at all times when mounted on a flag pole and also assure easy shift in position of the unfurled flag responsive to change in direction of wind.

A feature of the invention resides in the provision of a rod, which may be straight or have corrugations therein, on which a flag may be mounted, thereby to be retained in unfurled position.

Another feature of the invention resides in the use of a swivel or revolving attachment in combination with the flag mounting device whereby a flag in unfurled condition may readily rotate or swing about the axis of a flag pole when subjected to change in direction of affecting winds.

Other objects and features will be apparent from the following description of typical forms of the invention to be read in connection with the accompanying drawing in which:

Fig. 1 is a view, partly in section, of a flag mounted in accordance with applicant's invention and

Fig. 2 shows a modification of the mounting arrangement and

Fig. 3 is a cross-section on the lines 3—3 of Fig. 1, and

Fig. 4 is a cross-section on lines 4—4 of Fig. 2.

Considering the drawing, similar designations referring to similar parts, numeral 3a is a flag pole or staff having a ball bearing mounting 4 fitted about the upper extremity of the pole and resting upon stop 5 secured about the outer surface of the pole. Pin 6 is embedded in and projects from the upper extremity of the pole a desired distance. The pin is preferably provided with a threaded tip on which ornamental cap 7 is fitted in order to hold mounting 4 in place. However, if desired, mounting 4 may be secured as by screws to the upper extremity of the pole in which case the ornament may be omitted or may be arranged integral with mounting 4. Flag carrying rod 8 is attached to the mounting 4 preferably in a removable, dove-tail connection so that the rod may be fitted within and removed from the corresponding fitting on the mounting. As shown in Fig. 3, rod 8 fits within dove-tail connection 9, being firmly supported in position horizontally, so that the rod cannot sag. The result is that the rod readily swivels or rotates about the pole. Flag 10 has a hem 11 which fits over the rod 8. The lower left-hand corner

of the flag, as shown in Fig. 1, is attached to a ring 12 of a suitable material, said ring also fitting about the pole. The vertical portion of horizontal rod 13 is indicated by numeral 14.

In Fig. 2 a modified form of the invention is shown. The flag carrying rod has a cross-wise member 13 integral with a vertical member 14. A halyard 15 is secured to the rod at the upper end of element 14, as shown in Fig. 2. A pulley 16 is integral with mounting 4 and the halyard fits on the pulley so that the rod may be raised and lowered. Ring 17 serves the same function as ring 12 of Fig. 1 and it will be noted that the vertical element 14 of the rod rests against the mounting 4 so that it cannot be displaced substantially from a vertical position once the horizontal element 13 is in position.

Unlike straight rod 8 of Fig. 1, element 13 is wavy with the result that the flag is given an appearance as if it is waving in a wind, and this appearance is maintained at all times regardless of the condition of the wind.

In practice, a flag, in connection with the arrangement of Fig. 1, will have its upper portion hemmed and slipped upon rod 8. The ring will be slipped upon the pole and the rod slipped onto the receiving fitting. In places where permanent display is desired, the arrangement can be utilized to present a full appearance of a flag.

For outdoor use the arrangement of Fig. 2 is preferred, although the element 13 may be straight instead of wavy. In this way too the ring 17 is slipped about the pole and the halyard is then pulled in the ordinary manner to raise the rod to the top of the pole. The halyard will be secured as at 18, near the foot of the pole, thus retaining the rod in position at the top.

It will be apparent that regardless of the direction of the wind the flag veers around the pole due to the connection of the rod to the mounting. The rings permit the bottom of the flag to swing with the rest of it. Hence, wear on the flag is reduced to a minimum and the flag is at all times fully displaced in unfurled condition.

Since variations may be made in the manner of mounting, as well as in the structure and arrangement of the rod in connection with the mounting, applicant does not limit himself to the specific embodiments shown, except as indicated in the claims.

I claim:

1. In combination, a flag-pole, a flag, a rotatable device mounted at the upper extremity of the flag pole, a horizontal rod and a fitting at one end thereof making a dovetail connection

with one portion of the rotatable device in such manner that the rod is carried by and is freely rotated by said device about the pole, a ring attachment device, said ring attachment device being fitted loosely about the pole and attached to a corner of the flag adjacent the flag-pole, a pulley mounted on the swivel device and means in combination with the pulley and flag supporting device adapted to raise and lower the same.

2. In combination, a flag-pole, a flag, a rotatable device mounted at the upper extremity of the flag pole, a flag supporting device comprising a rod having a horizontal portion integral

with a vertical portion, means for removably attaching the rod to said rotatable device so that it is carried by the rotatable device and may be freely rotated by the device about the pole, a ring attachment device, said ring attachment device being fitted loosely about the pole and attached to a corner of the flag adjacent the flag-pole, a pulley mounted on the swivel device and means in combination with the pulley and flag supporting device adapted to raise and lower the same.

LINUS SCHILLINGER.
